Primary Examiner — Barbara Fox*Assistant Examiner* — Messina L Smith(74) *Attorney, Agent, or Firm* — NSIP Law(57) **CLAIM**

We claim the ornamental design for a cooktop, as shown and described.

DESCRIPTION

FIG. 1 is a front perspective view of a cooktop showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is an enlarged view of the encircled portion in FIG. 1;

FIG. 9 is an enlarged view of the encircled portion in FIG. 4; and,

FIG. 10 is an enlarged view of the encircled portion in FIG. 6.

The broken lines shown in the figures depict portions of the cooktop that form no part of the claimed design. The dot dash broken lines in the figures depict a boundary line and form no part of the claimed design.
